DESIGN FOR A CABINET FOR PICTURE AND SOUND PROJECTION MACHINE

Everett B. Eckland, Oak Park, Ill.

Application April 7, 1945, Serial No. 118,892

Term of patent 14 years

(Cl. D56—4)

To all whom it may concern:

Be it known that I, Everett B. Eckland, a citizen of the United States of America, residing at Oak Park, in the county of Cook and State of Illinois, have invented a new, original, and ornamental Design for a Cabinet for Picture and Sound Projection Machine, of which the following is a specification, reference being had to the accompanying drawing, forming part thereof.

The figure is a perspective view of a cabinet for picture and sound projection machine, showing

my new design. The side of the cabinet not shown is the same as the side shown and the back is plain and unornamented except for the horizontal medial bands or strips which continue around the rear.

I claim:

The ornamental design for a cabinet for picture and sound projection machine, as shown and described.

EVERETT B. ECKLAND.
